UNITED STATES PATENT OFFICE.

JAMES CHARLES POTTER, OF PAWTUCKET, RHODE ISLAND, ASSIGNOR TO POTTER AND JOHNSTON MACHINE CO., OF PAWTUCKET, RHODE ISLAND, A CORPORATION OF RHODE ISLAND.

AUTOMATIC TURRET-LATHE.

1,072,648.

Specification of Letters Patent.

Patented Sept. 9, 1913.

Application filed January 21, 1908. Serial No. 411,994.

To all whom it may concern:

Be it known that I, JAMES C. POTTER, a citizen of the United States, and resident of Pawtucket, in the county of Providence, and 5 in the State of Rhode Island, have invented a certain new and useful Improvement in Automatic Turret-Lathes, and do hereby declare that the following is a full, clear, and exact description thereof, reference being had to the accompanying drawings, in which—

Figure 1 is a top plan view of a turret lathe embodying my invention, the turret and chuck being omitted. Fig. 2 a front 15 elevation, partly in section, of the same; Fig. 3 a cross section on the line 3—3 of Fig. 2; Fig. 4 a detail view, partly in plan and partly in section, showing the slide reciprocating bar with the parts in the position they occupy at the beginning of the 20 forward movement of the slide; Fig. 5 a detail view in plan of a portion of the under side of the bar with the cam grooves; Fig. 6 a section on the line 6—6 of Fig. 5; Fig. 7 a rear elevation showing the gearing 25 at the head stock end; Fig. 8 an end elevation of a portion of the machine looking toward the head stock; Figs. 9 and 10 are detail views of the devices operated by the 30 star wheel for changing the gear connections; and Fig. 11 a section on the line 11—11 of Fig. 1, showing the clutch connection of the spindle.

My invention relates to feed mechanism 35 for lathes, and the type of lathe in which I have embodied my invention, is the familiar turret lathe in which a cam drum is employed to reciprocate the turret slide, and the particular object I have had in view 40 in making my invention, is to improve the machine which forms the subject of my United States Patent No. 880,916, dated March 8, 1908, in which machine there is provided a slide moving mechanism in addition to the cam drum, by means of which the length of feed or travel of the turret slide may be as great as desired, independently of the cam drum, the latter, and the additional slide moving mechanism, operating 45 in succession upon the slide, the one being placed in operative connection with the slide when the other is disconnected therefrom.

By my present invention, I am able to 50 operate the lathe at a higher speed than

heretofore, because the mechanism by which the turret slide is moved when the cam is not acting thereon, can be made to move the turret slide at a much higher speed than it can be moved by the cam, and I time the 60 movement of the cam drum so that the proper cam is in readiness to begin its work the instant that the other slide moving mechanism finishes its portion of the movement of the turret slide. 65

Referring now to the drawings, A designates the frame of a turret lathe; B the head stock, in which is journaled the spindle C, carrying the chuck e; D the slide on which is mounted the tool turret E; and 70 F the cam-carrying drum, all which parts are, or may be, of usual construction, and therefore need no particular description.

Attached to the bottom of the turret slide D, lengthwise thereof, is a bar G, the attaching means consisting of bolts H and a slot, so that, when desired, the slide may be shifted relative to the bar to change its position. On the inner, or forward end of the bar G and on the bottom thereof, is 80 a cam-engaging projection in the form of an anti-friction roller g which by the action of the cams f on the drum F moves the turret toward and from the head stock in the usual manner. As I have explained in 85 my former patent, the extent of travel of the turret slide by the cams f is a limited one and any increase in its travel by the use of the cams is objectionable because of its

compelling an increase in the height of the 90 machine, and yet the demands of the work on these machines requires an increase of the travel of the turret slide. I have solved this problem by the provision of slide-reciprocating means additional or supplementary to the cams, and in the embodiment of my invention shown in the accompanying drawings, such means consist of rack teeth g' on one side of the bar G, a pinion I in mesh therewith, and mounted 95 on the upper end of a short vertical shaft K, a bevel gear L on the lower end of said shaft K, two bevel pinion M meshing with the bevel gear on diametrically opposite sides thereof and loosely mounted on a short horizontal shaft N, with which they are adapted to be alternately clutched, so that the pinion I may be revolved in either direction, and a gear wheel o' on the shaft N, which by gears o² receives motion from a 100 105 110

shaft P extending longitudinally at the rear of the machine, and which; by a train of gears is revolved from a pulley-driven shaft journaled in bearings on the rear side of 5 the head stock, all as more fully described hereinafter.

Each of the bevel pinions M has a clutch face, and between them a clutch collar S is splined to the shaft N and is movable so that 10 it may clutch either or neither pinion there-to. Said collar S is engaged by a lever T on the lower end of a vertical shaft U, which at its upper end has an arm V having a roller v situated in a cam path or slot in 15 the slide-actuating bar G, said slot or cam being composed of a centrally disposed longitudinally extending straight path W, and two longitudinally extending straight paths W' and W² arranged on either side of 20 the transverse center of the bar, and connected with said centrally disposed path W by paths that diverge therefrom, and in one of said paths, as is common with this type of cam, there is a switch latch or gate w which 25 permits the arm roller v to pass from the centrally disposed path W into only one (the path W') of the other straight paths. Said other, parallel, straight paths are connected at their ends opposite the single, central path, and when the roller has traversed 30 the path W' it is moved to the other path W² (and the clutch collar S thereby shifted) by means of a coil spring X mounted in an extension of the roller-carrying arm V with 35 one end bearing thereagainst and the other end, through the medium of a closed-ended tube or casing z, bearing against a surface on the machine frame A. When the arm roller v is in the centrally disposed path W, 40 the clutch collar S is held in mid-position so that neither bevel pinion M is in mesh with the bevel gear L, and thus no motion be transmitted to the bar G thereby.

It will be seen that by the reciprocation of 45 the bar G, with its cam paths, the clutch collar S, so long as the arm roller v is in the centrally disposed path W, will be maintained in mid-position, and no movement be imparted to the turret slide by the piston I 50 and rack, or said collar will be shifted to clutch one or the other of the bevel pinions M to their shaft so as to revolve the rack-engaging pinion I and move the turret slide toward or from the work, according to which 55 of the bevel pinions M is clutched to its shaft, such rotation of the bevel pinion, and consequent travel of the turret slide, continuing so long as the arm roller v is in the respective cam path W' or W². During the time 60 the arm roller v is in the centrally disposed path W and of the consequent inaction of the rack-engaging pinion I, the turret slide is moved by the action of a cam f on the periphery of the cam drum F, and the movement of the turret slide at this time in one

direction is for feeding the tool while doing its work, while during the time the arm roller v is in one of the straight paths W' or W², none of the cams f of the drum F acts on the projection or roller g of the bar G, 70 and the travel of the turret slide is produced wholly by the rotation of the pinion I, and the extent of the travel of such slide is, of course, entirely dependent upon the length of the rack and of the straight paths W' 75 or W², which length may be any that is desired. The movement of the bar G and the turret slide during the time the clutch collar S is being shifted from one of its positions to another by the passage of the arm roller v 80 from the straight path W to the straight path W', and from the straight path W' back to the straight path W, is effected by the cam plates f on the drum F.

The positions of the straight paths W, W' 85 and W² with reference to the direction of travel of the turret slide are such that when the turret is at the extreme point of its travel away from the work, the arm roller v will lie in the end of the straight path W² nearest 90 the work, and that bevel pinion M which rotates the pinion I in the direction to move the turret slide toward the work will be clutched to its shaft and will remain so clutched until the arm roller v has traversed 95 the length of the path W² and reaches the switch latch or gate, at which time one of the feed cams f on the drum F will engage the projection or roller g on the bar G, so that further forward movement of the bar 100 G and the turret slide, and the shifting of the clutch collar F, to mid-position by the passage of the arm v to the inner end of the straight path W will be effected by the action of said cam f. This forward travel of 105 the turret slide while the arm roller v is in the straight path W² is utilized to bring the turret tool which is to be used into position to begin its work, and if, for example, such tool is a boring bar Y, it enables the portion 110 of the latter in advance of the cutters to pass through the work supported by the chuck and enter a pilot bushing in the end of the spindle, so that, so to speak, the turret and spindle will be tied together and the boring 115 bar rigidly supported at both ends while the cutting or boring is being done. It will, therefore, be evident that if the subject of work is a long piece, whether the amount of work to be done is long or short, I am enabled to rigidly support the tool-carrying bar at both ends. I have referred to the use 120 of a boring bar merely as an illustration, for, as will be seen from the illustration in Fig. 2 of the drawings, a tool Z for doing outside 125 work may be used, such tool Z being mounted upon a bar that at one end is secured to the turret. During the travel of the turret slide when the arm roller v is in the straight path W' the turret slide is moved to with- 130

draw the boring or tool supporting bar from the spindle or work to an extent, of course, corresponding with its movement when the arm roller v is in the straight path W^2 by the action of the rack and pinion, the extreme portion of the rearward travel of the turret slide being effected by one of the return cams f on the cam drum F .

The gearing for revolving the shaft P is such that the turret slide is moved at as high a speed as is desired, rearward from the work, until within a short distance of the end of its rearward travel, when its speed is reduced to give time for the automatic revolution of the turret, without danger of damaging the turret locking stud and to avoid damage, from the momentum of the parts at a high speed, in arresting the rearward travel of the turret slide and reversing such travel, and for the greater portion of its forward travel, after its reversal, the turret slide is moved at as high a rate of speed as desired. I will now describe the gearing by which I secure such movement of the turret slide. Journaled loosely on the shaft P , is a gear A' which is geared to the lathe spindle, which is revolved from a band wheel B' , keyed to a shaft B^2 journaled in bearings on the head stock, to which band wheel a belt runs from a counter shaft. A train of gears B^3 transmits motion from the pulley shaft B^2 to a shaft B^4 having a gear B^5 which meshes with the gear A' , and from the shaft B^4 by change gears B^6 power is transmitted to a shaft B^7 having a pinion B^8 which meshes with a gear B^9 on the spindle C , and which drives the spindle C through the clutch connection illustrated in Fig. 11, and which is similar to that shown in United States patent issued to Potter & Johnston Machine Co., No. 761,905, June 17, 1904. Connected to the gear A' by means of a sleeve C' , is a pinion D' that is in mesh with a gear E' on a shaft F' journaled in bearings on the head stock of the lathe. The gear E' is loose on the shaft F' , and has on one side a hub or collar G' , which forms one member of a clutch, the other member of the clutch being a collar I' which is keyed to the shaft and has clutch teeth or pins i' adapted to engage the hub G' by the sliding of the gear and its hub, so that when said clutch members are engaged, the shaft F' will be revolved by means of the pinion D' and its intermeshing gear E' . On the shaft F' , is a comparatively large gear K' , which meshes with a pinion L' on the shaft P , so that when the gear E' is clutched to the shaft F' , the shaft P will be revolved by means of the gear K' and the pinion L' , and at such a rate of revolution as to impart a high speed to the turret slide. The gear E' also has clutch teeth or pins e' adapted to engage a clutch hub or sleeve M' , journaled loosely on the shaft F' , and

connected to a gear N' , which is in mesh with a gear O' , of like diameter keyed to the shaft P . The gear N' , when its clutch hub or sleeve is interlocked with the gear E' , will be revolved by the gear E' , and as at this time the gear E' is unclutched from the shaft F' , the revolution of the shaft P will be derived from the intermeshing of the gears N' and O' , and such revolution will be at the rate to impart the slow movement to the turret slide, which is desired, to give time for the automatic revolution of the turret and the reversal of the travel of the turret slide.

The operation of the clutches by which the gear connections are changed, is effected automatically. For sliding the gear E' , the mechanism employed is as follows: Engaging an annular groove in the gear hub or collar G' , is one arm of a lever p' , pivoted to a bracket on the frame A of the machine, and connected to the other arm of said lever p' , is a yoke-shaped sleeve P' that is slidably mounted on a shaft Q' placed in bearings on the frame A , so as to lie parallel with the lathe spindle. Fixed to the shaft Q' , at one side of the sleeve, is a sleeve or collar R' , which on its end next the yoke-shaped sleeve P' , has several inclined or cam surfaces adapted to co-act with similar surfaces on the adjacent end of the yoke-shaped sleeve, and by the revolution of the shaft Q' , the cam surfaces acting upon each other will move the yoke-shaped sleeve longitudinally, and thereby move the lever p' in one direction. The yoke-shaped sleeve is moved in the opposite direction to rock the clutch lever p' in the reverse direction, by means of a coil spring S' . The shaft Q' is rotated intermittently, or step by step, so that the to and fro movement of the yoke-shaped sleeve will take place in succession and with an interval of time between its movements in opposite directions. To so rotate the shaft Q' , it has upon one end a star wheel T' , whose teeth are adapted to be engaged in succession, by pins or studs u' , secured to the side of a wheel U' , fixed to the cam drum shaft V' . The movements of the yoke-shaped sleeve P' are transmitted to the clutch lever p' , by means of a cam path p^2 formed in an arm of said sleeve P' , which engages a stud or roller on one arm of a bell crank lever p^3 , the other arm of said bell crank lever being pivotally connected to one end of a lever p^4 , whose other end is pivotally connected to an arm p^5 on the shaft p^6 of the clutch lever p' . As is usual with the class of machines to which my invention relates, the cam drum is driven by power taken from a band wheel c on the lathe spindle C , the belt from the band wheel c being run to a pulley W' of a differential gear, all as shown in the United States patent issued to Potter & Johnston

Machine Co., No. 761,905, June 17, 1904. Besides driving the cam drum from the lathe spindle through the differential gear, the cam drum is driven at a higher rate of speed than that imparted to it through the differential gear, by a train of gearing which includes a pinion X' upon the shaft F' , which pinion meshes with a gear Y' , from which motion is transmitted to the cam drum. Although, as will be seen, both the lathe spindle and the shaft F' are geared to the cam drum, and the gear connection between the shaft F' and the cam drum is such that a higher speed of revolution is imparted to the cam drum, than from the lathe spindle, this is possible, because just as in the case of the machine in the above mentioned patent, and as illustrated in Fig. 11, a form of clutch mechanism is employed with the lathe spindle C , which permits the lathe spindle C to revolve independently of and faster than its driving mechanism revolves it, such faster revolution of the lathe spindle C taking place when the cam drum receives its motion from the shaft F' .

It will be seen that the connection from the driving member, such as the pulley B' on the shaft B^2 , to the turret slide for imparting the return movements to said slide, is independent of the connection from said driving member to the work spindle, so that said return movements will not be in any way affected by variations in the speed of the spindle, but will instead remain constant and uniform so long as the speed of the driving member remains constant. It will also be seen that the feeding movements of the turret slide are in unison with or in harmony with the speed of the work spindle, so that when, for example, different change gears are used, the speed of the spindle is changed, the feeding movements of the turret slide will be correspondingly changed.

The means by which motion is transmitted to the drum F from the shaft F' through the pinion X' and gear Y' , are as best shown in Figs. 2 and 8, a pinion I^{10} alongside the gear Y' , a gear H^{10} with which said pinion meshes on a shaft G^{10} having at one end a pinion F^{10} that meshes with a gear E^{10} on the cam drum F . As will be seen by reference to Patent No. 761,905, hereinbefore referred to, the pins u' of the speed changing wheel U' are adjustable, so that thereby the time of shifting the gear connections with the shaft F' may be fixed as desired, and thus the time when the return movement of the turret slide at the highest speed through the gears X' and Y' may be determined. Thus, since the shaft F' is geared directly with the cam drum F , so that the latter need not be driven through the differential gear, the pins u' of the speed changing wheel may be adjusted so as to render the shaft F' active to drive the cam drum for the return

movement of the turret slide as soon as the work of a turret tool has been finished.

The pinion A' is preferably provided with a clutch x' , by which it may be disconnected from the shaft F' , when it is desired to turn the cam drum by hand, so as to avoid moving the parts geared to the shaft F' , which would be necessary were the pinion X' fast to the shaft F' .

The mechanism for automatically clutching and unclutching the gear N' with the gear E' , is as follows: Engaging the hub or sleeve M' of the gear N' , is a lever Z' , which normally tends to move the gear N' and its clutch hub M' to a position where it will be unclutched from the gear E' , as by means of a spring or weight z^2 . For moving said gear N' and its clutch hub in the opposite direction, to engage the same with the gear E' , a pitman or rod A^2 is connected to and extends from said lever to a bell crank lever B^2 pivoted to the machine frame, which has on one of its arms a stud or roller b^2 which engages a cam path g^2 in the bar G of the turret slide moving mechanism, which cam path has such form as to produce the shifting of the gear N' and its clutch hub M' into engagement with the gear E' when the turret slide is traveling from the work and at the time when the speed of travel of the turret slide is to be reduced, and to maintain the engagement between the clutch hub of gear M' and the gear E' until the revolution of the turret, which takes place at the lower speed, is accomplished, and the turret slide has reversed its direction of travel and has traveled a short distance toward the work, whereupon the gear N' and its clutch hub M' , will be moved to disengage the same from the gear E' , at which time also the gear E' will be clutched to the shaft F' , through the star wheel mechanism I have already described, to place the high speed gearing for the turret slide into operation, as well as the high speed gearing for revolving the cam drum.

The operation of the machine illustrated and described, is as follows: The travel of the turret slide while work is being done, is produced by engagement of the proper cam plate of the cam drum with the stud or roller g of the turret slide, the revolution of the cam drum at such time being caused by the belt connection between the lathe spindle and the differential gear, and the return movement of the turret slide, after the completion of the work of the tool, is likewise produced by the appropriate cam plate of the cam drum until a point is reached in the rearward travel of the turret slide, when by the action of the cam path in the bar G upon the clutch operating lever T , the turret slide is coupled to the shaft P , whereupon the further rearward movement of the turret slide is at the high rate of speed im-

parted by the shaft P, due to the coupling of said shaft to the shaft F' through the pinion L' and gear K'. At the same time that the shaft P is coupled to the turret slide 5 bar G, the clutch collar G' on the shaft F' is moved by the star wheel actuated devices to clutch the gear E' to the shaft F', so that the latter may be driven by the gear connections hereinbefore described, from the 10 head stock shaft having the band wheel B'. Since the shaft F' is now being driven or revolved as described, the pinion X' on the shaft F' through the gear Y', imparts motion to the cam drum shaft through the differential gear at a higher speed than the 15 cam drum shaft is driven by its belt connection with the lathe spindle, so that the revolution of the cam drum is increased to keep pace with the increased rate of travel 20 of the turret slide, in order that a cam plate f of the cam drum may be in readiness to engage the stud or roller g on the bar G at the proper instant without any loss of time. The rearward movement of the turret slide 25 at the high speed, through the instrumentality of the shaft F', is continued to the point when it is desired to slow down the rearward travel of the turret slide, to enable the automatic revolution of the turret at 30 such a rate of speed as not to result in damage to the locking stud or other parts, and also to avoid the shock which would result from the arresting and reversing of the travel of the turret slide with its heavy 35 parts at a high speed. To effect this slowing down of the motion of the turret slide, the clutch collar G' is shifted to disconnect the gear E' from the shaft F', which operation is produced by the action of the star 40 wheel actuated mechanism, and by the shifting of the clutch hub M' of the gear N', into engagement with the clutch pins or studs on the gear E', which movement of the clutch hub M' is produced by the cam path 45 g² in the bar G, which operates the bell crank lever B², thus gearing the shaft P to the gear N', which meshing with the gear O' on the shaft P, revolves the latter at the lower speed desired. As the gear E' is at 50 this time unclutched from the shaft F', the latter ceases to be the means for revolving the cam drum, which is again driven by its belt connection with the lathe spindle. The rearward travel of the turret slide at the 55 slow speed, being completed, and its travel reversed, the clutch hub M' is shifted in the direction to disengage it and the gear wheel E', by the operation of the cam path g² in the bar G, and at the same time the clutch 60 hub of the gear E' is moved by the action of the star wheel actuated devices to again clutch the gear wheel E' to the shaft F', to couple the turret slide and the cam drum again to the high speed gearing, to move the 65 turret slide forward to the point where the

work of the tool is to begin, which point being reached, the turret slide stud or roller g will be immediately engaged by the proper feeding cam plate on the cam drum, whereupon the further onward travel of the turret slide will be effected by said cam drum. It will be seen that as the shifting of the clutch hub M' to render the gear N' active or inactive upon the shaft P, is accomplished by mechanism that is operated from the turret slide, the change of speed of the turret slide is certain to occur at the proper time in the travel of the turret slide. 70

It is to be understood that though I have illustrated and described in detail the construction of a particular machine, in which I have embodied my invention, the scope of my invention is not limited or restricted to the machine of such or any particular construction. 80

Having thus described my invention, what I claim is:

1. In a feed mechanism for feeding a tool, the combination of a traversable tool holder, a drum having cams arranged to act in succession to move the tool holder during one part of its traverse for the performance of work by the tool, separate means arranged to be effective upon said tool holder to move it during another part of its traverse, at a different speed, gearing for revolving the drum at working speed, other gearing for revolving the drum at a different speed, and means to drive the drum through one of said gearing or the other. 90

2. In a feed mechanism for feeding a tool, the combination of a traversable tool holder, mechanism for moving the tool holder during one part of its traverse for the performance of work by the tool, separate mechanism arranged to be effective upon said tool holder to move it during another part of its traverse, and means to vary the speed at which the tool holder is moved by said separate mechanism to cause it to move at different speeds during different portions of its travel. 105

3. In a feed mechanism for feeding a tool, the combination of a turret slide, a cam drum for moving the slide while work is being done, a separate mechanism for imparting movement of the slide at other times, and automatic means for slowing down the movement of the slide by said separate mechanism at the end of its travel from the work. 115

4. In a feed mechanism for feeding a tool, the combination of a traversable tool holder, a cam drum to move the tool holder during one part of its travel, separate means to move said tool holder during another part of its travel, gearing for revolving the drum for the performance of work, other gearing for revolving the drum at a higher 125 speed. 130

rate of speed, automatic means to change the gear connections for revolving the drum so that said higher rate of speed is imparted to the drum when the tool holder is 5 moved by said separate means.

5. In a feed mechanism for feeding a tool, the combination of a traversable tool holder, a cam drum to move the tool holder during one part of its travel, separate 10 means to move said tool holder during an other part of its travel, gearing for revolving the drum for performing work, other gearing for revolving the drum at a higher rate of speed, connected with said 15 separate tool holder moving means, and means for changing the connection between said other gearing and the drum so that the drum will revolve at the higher speed when said separate means is acting on the tool 20 holder.

6. In a feed mechanism for turret lathes the combination of a turret slide, two slide moving means effective upon the slide to move it during different parts of its travel 25 one of which means moves the slide when work is not being done, means for varying the speed of the slide during its travel when work is not being done, and mechanism operated by the slide for controlling said 30 speed-changing means.

7. The combination of the lathe spindle, the turret slide, a cam drum, a driving mem-

ber, a train of gearing connecting the spindle and the cam drum, a separate train of 35 gearing connecting the spindle and the turret slide, other gearing between the driving member and the cam drum, and means to change the gear connections between the driving member and the cam drum, whereby the cam drum may be revolved for the 40 performance of work, and revolved at a higher speed when work is not being performed.

8. In a feed mechanism for turret lathes, the combination of the lathe spindle, the 45 turret slide, a cam drum, connections between the cam drum and the turret slide, a train of gearing connecting the spindle and the turret slide, a separate train of gearing connecting the spindle and the drum, other 50 gearing between the drum and the slide-actuating gearing, and means to change the gear connections of the drum so that at one time it is geared to drive it for the performance of work, and so that at another time 55 it is geared to drive it at a higher speed when work is not being performed.

In testimony that I claim the foregoing I have hereunto set my hand.

JAMES CHARLES POTTER.
